UNITED STATES PATENT OFFICE

91,553

DESIGN FOR A COMBINED DIRECTIONAL AND TAIL OR DRIVING LAMP FOR MOTOR VEHICLES

Edward T. Condon, New York, N. Y.

Application June 7, 1933. Serial No. 48,303

Term of patent 7 years

To all whom it may concern:

Be it known that I, EDWARD T. CONDON, a citizen of the United States, residing in New York, in the county of New York and State of New York, have invented a new, original, and ornamental Design for a Combined Directional and Tail or Driving Lamp for Motor Vehicles, of which the following is a specification, reference being had to the accompanying drawing, forming part thereof.

In the drawing, Fig. 1 is a perspective view and Fig. 2 a front elevation, on a reduced scale, of a

combined directional and tail or driving lamp for motor vehicles, showing my new design, the device represented thereby being symmetrical in cross-section throughout and the dominant feature being constituted by the intersection of portions of the arrow-head by the central lamp.

I claim:

The ornamental design for a combined directional and tail or driving lamp for motor vehicles, as shown and described.

EDWARD T. CONDON.
